Fig. 10

Fig. 11

FIG. 1 is a front elevation of a vibrator for material handling showing my new design;

FIG. 2 is a rear elevation thereof;

FIG. 3 is a top plan view thereof;

FIG. 4 is a bottom plan view thereof;

FIG. 5 is a side elevation of a second modified embodiment of the vibrator;

FIG. 6 is a front elevation thereof;

FIG. 7 is a side elevation of a third modified embodiment of the vibrator, the rear being identical therewith;

FIG. 8 is a cross-section taken on line 8-8 of FIG. 7;

FIG. 9 is a side elevation of the embodiment shown in FIGS. 1 and 2;

FIG. 10 is a rear elevation of the embodiment shown in FIGS. 5 and 6; and

FIG. 11 is a side elevation of the embodiment shown in FIG. 7.

The broken lines are shown for illustrative purposes only.

I claim:

The ornamental design for a vibrator for material handling or the like, as shown and described.
